UNITED STATES PATENT OFFICE.

EUGENE F. KING, OF GUILFORD, NORTH CAROLINA.

PACKAGE-TIE.

1,144,211.

Specification of Letters Patent. Patented June 22, 1915.

Application filed August 28, 1914. Serial No. 859,056.

To all whom it may concern:

Be it known that I, EUGENE F. KING, a citizen of the United States, residing at Guilford, in the county of Guilford and 5 State of North Carolina, have invented certain new and useful Improvements in Package-Ties, of which the following is a specification.

This invention relates to package ties, and 10 one of the principal objects of the invention is to provide a package tie with means for positively engaging and clamping the cord when in tied position, for preventing accidental loosening or withdrawal of the same.

15 Another object of the invention is to provide a package tie having a resilient cord engaging tongue, and a clamping sleeve adapted to be moved into locking position over said tongue during the process of tying 20 a package, for positively locking the tongue into engagement with the cord.

A further object of the invention is to provide a package tie of the class described, which may quickly and easily be undone, 25 by pulling the cord in a single direction subsequently to the unlocking of the tongue.

Still another object of the invention is to provide a tie which will be extremely simple, durable, efficient in operation and inexpensive to manufacture.

With these and other objects in view which will become apparent as the description proceeds, the invention resides in the construction, combination and arrangement 35 of parts, hereinafter more fully described and claimed, and illustrated in the accompanying drawing, in which like characters of reference indicate like parts throughout the several figures, of which—

40 Figure 1 represents a top plan view of a tie constructed according to my invention, showing the first step in the operation of fastening the same. Fig. 2 represents a view similar to Fig. 1 showing another step in the operation. Fig. 3 represents a view similar to Fig. 1 showing the position of the tie upon completion of the fastening operation. Fig. 4 represents a perspective view of the tie in unlocked position. Fig. 5

45 represents a bottom plan view of the same. Fig. 6 represents a vertical central longitudinal sectional view taken through the tie showing the same in locked position, and Fig. 7 represents a vertical transverse sec-

tional view taken on the plane indicated by 55 the line 7—7 of Fig. 6.

Referring more particularly to the drawing, the tie comprises a body 5, a locking tongue 6, a clamping sleeve 7, a cord clip 8 and a cord 9.

The body, locking tongue, and cord clip are formed of a single strip of metal bent to the proper form.

The body is in the form of a flat strip having parallel longitudinal edges 10. The 65 said strip is doubled upon itself near one end to form a loop 11, the extreme end 12 of the strip lying flat upon the body portion 5 and being welded or otherwise suitably maintained in intimate relation therewith. 70

The locking tongue 6 overhangs body 5 for the greater portion of the length thereof, said tongue being connected with the body at its opposite end from the cord clip 8, by a looped portion 13 off-set to one side 75 of the body and lying parallel therewith. The tongue at its free end 14 is rounded, and the extreme end 12 of the cord clip is provided with an arcuate notch of a curvature equal to the curvature of the end 14. This 80 arrangement allows for the locking tongue being depressed upon the body portion whereby its upper surface will lie flush with the upper surface of portion 12 of the cord clip, so that the clamping sleeve 7 may be 85 slid from said clip along the body portion and over the locking tongue in a manner to be hereinafter set forth. Previously to the tying process the tongue, by reason of its resiliency lies above and in spaced relation to 90 the body 5.

The under side of cord clip 8 at the loop 11, is provided with a key hole slot 15. Cord 9 at one end is knotted and the knot dropped through the enlarged portion of slot 15, and 95 the cord is then drawn to bring the knot adjacent the smaller end of the slot. This arrangement provides means for easily equipping the tie with the cord, and at the same time prevents accidental displacement 100 or unloosening of the cord from the tie.

The clamping sleeve 7 encircles the tie and when the latter is not in use, is disposed upon the cord clip adjacent the loop 11. The initial bulging of the loop adjacent the 105 clamping sleeve provides a sufficient grip to prevent accidental slipping of the sleeve along the tie and at the same time allows

of the easy manipulation of said clamping sleeve. A hook 16 is provided on the sleeve and projects toward cord clip 8. The hook comprises an inclined shank 17 and a substantially flattened and rounded head 18. This design is adapted to prevent catching of the hook in the raiment of the handler of the package or in other objects against which the package may come in contact. 5 The tie is provided at the end opposite cord clip 8, with registering openings in the body and locking tongue, so that the tie may be hung or suspended in a convenient position to be used when desired. 10 The operation of the device may be briefly described as follows: The tie is placed upon one side of a package 19 in the position indicated in Fig. 1. The cord is then passed around the package in the direction of the tie, and is then inserted between the tongue 6 and the body 5, and is drawn to the left and passed around the package laterally thereof, again slipped between the tongue and body and pulled toward the operator at 15 an angle as indicated in Fig. 1. This pulling action draws the cord to the desired tension on all sides of the package. The left thumb of the operator is then placed upon the portion of the cord overlying the near end of the tongue as indicated at 20 and the cord is then looped about the tongue in the position shown in Fig. 2. The left thumb is then shifted to depress the locking tongue upon the body, and the cord is passed 25 along side the body and engaged upon hook 16 of the clamp sleeve. A pull upon the cord toward the operator then draws the sleeve down and over the locking tongue, into the position shown in Fig. 3, and the cord may 30 then be released. By this operation it will be seen that the cord is utilized in drawing the clamp sleeve into locking position upon the tongue, during the process of fastening the tie. When it is desired to undo the 35 package, the clamping sleeve may be engaged by one of the thumbs of the operator and shoved off of the locking tongue upon the cord clip. The cord may then be pulled away from the operator in a single direction 40 thus disengaging all of the cord from the tie with the exception of that portion initially slipped between the tongue and body. This action sufficiently loosens the 45 cord to allow of the ready removal of the tie from the package. 50

It will be noted that the off-set parallel loop 13 provides a guide for maintaining the portions of the cord adjacent said loop, one portion 21 lying in alinement therewith and 55 the other portion 22 at right angles thereto, in these relative positions when the tying process is completed.

By reason of the free end of locking tongue 6 being rounded, abrasion or cutting 60 of the cord during the process of undoing

the tie is prevented. The fact that the cord may be unfastened by simply pulling the same in one direction is a great advantage, since it allows of the almost instantaneous removal of the tie.

70

Although I have described the preferred embodiment of my invention, I may desire to make such changes in the construction, combination and arrangement of parts thereof as do not depart from the spirit of 75 the invention and the scope of the appended claims.

I claim:—

1. A package tie comprising a flat body portion, a resilient locking tongue overlying 80 one end of the body portion, an off-set loop lying in parallel relation with said body and connecting one end of the tongue with the adjacent end of the body, a cord clip at the opposite end of the body, said clip comprising a loop formed by doubling one end of the body upon itself, a key hole slot provided longitudinally of the loop on the side of the body opposite said locking tongue, a cord having a knot at one end disposed in said key hole slot, a clamping sleeve normally positioned upon the doubled end of the body and adapted to be slipped over said locking tongue when the latter is depressed against the body, and a hook provided on said clamping sleeve adapted to be engaged by the cord for operating the sleeve during the process of fastening the tie.

90

2. A package tie comprising a flat body, a resilient locking tongue connected with the 100 body and disposed over the same at one end thereof, a cord clip formed on the opposite end of the body, a cord connected to said clip and adapted to be passed between the locking tongue and body during the process of fastening the tie, a clamping sleeve carried by the tie adapted to be slipped over the locking tongue for clamping the same against the cord, and means carried by the clamping sleeve and adapted to be engaged by the cord for operating said clamping sleeve during the process of fastening the tie.

105

3. In a package tie the combination of a body, a locking tongue disposed in spaced 115 relation over the body near one end and adapted to be forced into engagement with said body, a flexible element carried by the body and adapted to be wound about the package, said flexible element adapted to be engaged between the tongue and body, and a sleeve slidably disposed upon the body and adapted to be operated by the flexible element whereby to be slipped over said tongue for locking the same against the body, whereby to hold the flexible element against slipping.

120

4. A package tie including a body, and a locking tongue, a flexible element adapted 125 to be engaged between the locking tongue 130

and body during the process of fastening the tie, and a sliding sleeve operable by the flexible element for locking said tongue against the body whereby to clamp said

said sleeve being operable by the flexible element during the process of fastening the tie for locking said flexible element against the body.

5 flexible element in place.

5. A package tie comprising a body, a flexible element carried thereby, and a lock including a tongue and a clamping sleeve,
